UNITED STATES PATENT OFFICE.

PAUL B. RASH, OF WILMINGTON, DELAWARE.

DISPLAY FRAME.

Application filed December 12, 1922. Serial No. 606,375.

To all whom it may concern:

Be it known that I, PAUL B. RASH, a citizen of the United States, residing in Wilmington, Delaware, have invented a Display Frame, of which the following is a specification.

One object of my invention is to provide a frame for use in displaying matter, particularly advertising, which is subject to frequent change, the construction being such as to facilitate the changing operation.

Another object of the invention is to provide a frame that will accommodate practically all kinds of material upon which the advertising matter may be depicted, irrespective of flexibility or inflexibility, its thickness, or transparency.

A further object is to provide a temporary mounting for advertising matter capable of retaining the sheet or other body upon which the advertising matter is shown firmly in a flat stretched condition without the use of a backing and in such manner as to give the appearance of a permanent mounting.

A further object is to provide a frame which dispenses with the backing commonly found in frames to permit the display of transparent and semi-transparent subjects by means of a source of light at the rear of the frame.

The structure by means of which these and further objects are accomplished is illustrated in the attached drawing, in which:

Figure 1, is a view in perspective of the assembled frame;

Fig. 2, is a view in perspective of the facing portion of the frame;

Fig. 3, illustrates in perspective the back clamping bars of the frame in their normal relative positions;

Fig. 4, is a fragmentary perspective showing one corner of the assembled frame;

Fig. 5, is a section on the line 5-5, Fig. 4, and

Fig. 6, is a perspective view of one of the clamping elements.

With reference to the drawings, the device comprises in the present instance a substantially rectangular frame 1 which may be made as ornamental as desired. Although in the present instance the frame is

rectangular, it will be noted that it may assume any form suited to the particular requirements. The frame is preferably a comparatively thin one, and is provided at various spaced points around its periphery with slots or recesses 2 which extend inwardly from the outer edges of the frame. In the present instance, as clearly illustrated in Fig. 2, the rectangular frame is provided with two of the slots 2 in each side and at the top and bottom of the frame.

For use in conjunction with the frame 1 is a correspondingly shaped sectional frame consisting of side bars 3, 3, and top and bottom bars 4, 4, which bars are illustrated in Fig. 3. These bars are in the present instance of the same thickness as the frame 1, and are provided with slots 5 similar to the slots 2 in the frame 1, and similarly spaced so that when the bars 3 and 4 lie against the backs of the corresponding sides of the frame 1, the said recesses 2 and 5 are brought into conjunction. These slots 2 and 5 are adapted for the reception of U-shaped clamping elements 6, 6, which are inserted as best illustrated in Fig. 5, and thereby clamping the bars 3 and 4 tightly against the side of the frame 1, as shown in Figs. 1, 4 and 5. One of the clamping elements is shown in perspective in Fig. 6, and is preferably made of metal or similar resilient material which tends to resist separation of the legs of the clamp such as occurs as when the clamp is inserted in the slot, a tension accordingly being exerted by the clamp holding the bars 3 and 4 tightly to the frame 1.

In utilizing this device, the sheet or plate, or other object, which carries the advertising or other matter, is laid against the back of the frame 1, the bars 3 and 4 then one at a time being placed in their proper positions against the back of the body and the clamps inserted in the slots whereby the sheet or plate is clamped firmly between the frame and the said bars, which latter with the clamps 6 constitute in effect individual clamps bearing at different points against the sheet which they confine. Owing to the wide bearing surfaces of the bars and the gripping force exerted by the clamps 6, it is possible to maintain any form of sheet or plate regardless of flexibility or fineness of

texture in a flat stretched condition, giving the appearance of a permanent mounting. At the same time, it is an extremely simple operation to remove one sheet from the ⁵ frame and to insert another.

It will be apparent that by use of the clamping bars 3 and 4, the effective gripping surface of the clamp 6 is greatly increased, which makes possible the use of materials ¹⁰ in the advertising body of extremely fragile texture without injury.

It will further be noted that by reason of the nature of the clamping elements, the back of the frame is left open for the use ¹⁵ of the display as a transparency. The frame is an extremely inexpensive one, but very effective, and permits the constant changing of displays without injury either to the frame or the displayed object. The frame ²⁰ may be in numerous sizes for the reception of different sizes of advertising matter, and may be suspended from the wall after the fashion of the ordinary picture mounting, or may be supported in an upright position

on a stand of suitable type or by means of a ²⁵ strut at the back.

I claim:

1. The combination with an integral facing frame, of a backing frame having substantially the same dimensions as the said facing frame and comprising a plurality of sections independent both of each other and of the facing frame, and means for independently and detachably clamping the said sections to the facing frame. ³⁰

2. The combination with an integral facing frame, of a backing frame having substantially the same dimensions as the said facing frame and comprising a plurality of sections independent both of each other and of the facing frame, correspondingly placed recesses in the end edges of the facing frame and of the sections of the backing frame, and resilient clamping elements adapted to occupy the recesses and to secure the said ⁴⁰ sections to the facing frame. ⁴⁵

PAUL B. RASH.
